ARRANGEMENT FOR APPLICATION OF
DRIVING BOX WEDGE BOLTS

Joseph E. Bennett, Atlanta, Ga.

Application August 31, 1931. Serial No. 560,513

5 Claims. (Cl. 105—81)

This invention relates to locomotives and has special reference to wedge adjusting bolts for frame pedestals.

Locomotive frames are provided with upper and lower members connected by pairs of upright members forming slots for the reception of the journal boxes for the driving axles. A wedge serves to hold the journal box against the knocking produced by side stops. Because of the interruption of the bottom frame member at the pedestals or slots there is a tendency for the frames to break these pedestals and this tendency is resisted by a tie bar or binder spanning the bottom of each slot and bolted to the bottom of the lower frame member at each side of the pedestal. The wedges are usually adjusted by bolts passing through the tie bars and connected removably to the wedges.

In many previous arrangements breakage of a bolt or wedge necessitates removal of the tie bar or binder for repairs. This is highly objectionable because of loss of time and because of the practical impossibility of restoring the binder to exactly the same position which it occupied before removal, with the consequent spreading or drawing together of the pedestal legs and the resultant strain on the upper frame member.

One important object of the invention is to provide an improved device of this character wherein such repairs may be effected without removal of the tie bar or binder.

Other designs have been made in which the binder is bored or slotted to receive a sleeve through which the adjusting bolt extends. Such designs are objectionable since the opening for the sleeve has to be made much larger than the bolt size and either the binder is weakened by a large opening or the bolt has to be made too small to have proper strength.

A second important object of the invention is to provide an improved arrangement for this purpose wherein a bolt of proper size may be used without unduly weakening the binder.

In one form of such a device provision is made for a bolt of proper size working in a slot in the tie bar, but no adequate provision is made for preventing accidental displacement of the bolt from its proper position.

A third important object of the invention is to provide an improved device of this character wherein there is provided a novel arrangement of parts especially designed to prevent accidental displacement of the bolt.

With the above and other objects in view the invention consists in general of certain novel

details of construction and combinations of parts hereinafter fully described, illustrated in the accompanying drawings and specifically claimed.

In the accompanying drawings like characters of reference indicate like parts in the several views, and:

Figure 1 is a side elevation of a portion of a locomotive frame showing the invention applied thereto.

Figure 2 is a section on the line 2—2 of Figure 3.

Figure 3 is a section on the line 3—3 of Figures 1 and 2.

Figure 4 is a section on the line 4—4 of Figure 2.

Figure 5 is a section on the line 5—5 of Figure 2.

Figure 6 is a detail view showing a locking plate used herewith.

In the embodiment of the invention as here shown, there is disclosed a portion of a locomotive frame having an upper member 10 and 75 spaced sections 11 of the lower member, these sections being connected to the upper member by pedestal legs 12. A binder or tie bar 14 extends across the space at the bottom of the legs 12 and the frame is provided with tapered lugs 15 80 which engage in correspondingly shaped notches 16 formed in the top of the binder. Bolts 17 pass through the ends of the binder 14 and through the bottom members 11 of the frame and rigidly secure the binder in position. A wedge 18 bears 85 against one of the pedestal legs 12 and between this wedge and the other pedestal leg is a journal box 19 which is free to slide up and down in the pedestal. The wedge is adjustable vertically on the leg 12 and the contacting surfaces of the 90 leg and wedge are inclined to the vertical in such manner that the wedge moves toward the remaining leg as it is moved upwardly. By this means the sliding fit of the box 19 may be regulated so that the box moves freely up and down 95 but yet cannot move laterally to produce a knock.

In the lower end of the wedge is a T-shaped slot 20 wherein is normally fitted the head 21 and flattened upper part 22 of the shank of a wedge adjusting bolt 22' which extends downwardly through a slot 23 formed longitudinally in the binder, this slot being of just sufficient width to freely accommodate the bolt body. Moreover, the head of the bolt is laterally flattened as by grinding off the sides of the head of 105 a square headed bolt until it is reduced to such width that it will pass through the slot 23. This flattening of the head is effected at right angles to the flattening of the shank at 22. The lower part or stem of the T-slot 20 is just sufficiently 110

- wide to accommodate the flattened portion 22 so that when the bolt is engaged in the slot it cannot rotate. Bolts 24 extend through the binder in spaced relation to the respective ends of the slot 23. The heads of these bolts may, if desired, be countersunk into the binder. Fitted on the lower ends of these bolts is a locking plate 25 which is provided with openings 26 for these bolts and with an opening 27 for the adjusting bolt.
- 10 When this plate is thus fitted on the bolts it locks the adjusting bolt from movement out of the slot 20, but when this plate is removed the adjusting bolt may be moved along the slot to be freed from the wedge and it may then be given 15 a quarter turn and withdrawn through the slot 23. A yoke or bridge piece 28 is also provided with suitable openings for the bolts 22' and 24 and above and below the bridge piece the bolt 22' carries the adjusting nuts 30 by which the 20 bolt 22' and consequently the wedge 18 may be vertically adjusted. On the lower ends of the bolts 24 are nuts 29 by means of which both bridge piece and locking plate are held securely in position.
- 25 With this construction it is merely necessary, for repairs or replacements of the bolt 22', to remove the nuts 30, whereupon the nuts 29 may be turned to free the bolt 22' from pressure, the lower nut being entirely removed. When the 30 bridge piece and locking plate are dropped off, the bolt 22' can be withdrawn through the slot 23. This is accomplished by moving the bolt laterally out to the end of slot 20, tilting its head out of the slot 20 and turning the head, so that it may 35 be withdrawn through the other slot 23.
- There has thus been provided a simple and efficient device of the kind described and for the purposes specified.
- It is obvious that changes may be made in the 40 form and construction of the invention without departing from the principles thereof. It is not, therefore, desired to confine the invention to the exact form herein shown and described but it is desired to include all such as come within the 45 scope claimed.
- What is claimed as new, is:—
1. In a device of the kind described, a side frame having a pair of spaced pedestal legs, a binder spanning the space between the lower ends 50 of said legs and provided adjacent one leg with a slot extending vertically through and longitudinally of the binder, a journal box wedge bearing on the inner face of the leg adjacent said slot and provided at its lower end with a T-shaped slot opening through the bottom of the wedge, bolts 55 securing said binder to the frame, an adjusting bolt having its head in the head portion of the wedge slot and its shank extending downwardly through the stem portion of the wedge slot and down through the slot in the binder, a locking plate having an opening therein through which the lower end of said bolt passes to fit closely therein, and bolts securing the locking plate against the under side of the binder to hold the bolt 60 against movement longitudinally of the slot, a bridge plate carried by the last mentioned bolts and through which said adjusting bolt passes, adjusting nuts on the adjusting bolt above and below the bridge piece, the shank of said adjusting bolt being flattened in the part engaging in the stem portion of the wedge slot to fit closely therein and prevent rotation of the bolt.
  2. In a device of the kind described, a side frame having a pair of spaced pedestal legs, a binder spanning the space between the lower ends of said legs and provided adjacent one leg with a slot 70 extending vertically through and longitudinally of the binder, a journal box wedge bearing on the inner face of the leg adjacent said slot and provided at its lower end with a T-shaped slot

opening through the bottom of the wedge, bolts securing said binder to the frame, an adjusting bolt having its head in the head portion of the wedge slot and its shank extending downwardly through the stem portion of the wedge slot and down through the slot in the binder, a locking plate having an opening therein through which the lower end of said bolt passes to fit closely therein, bolts securing the locking plate against the under side of the binder to hold the bolt against movement longitudinally of the slot, a bridge plate carried by the last mentioned bolts and through which said adjusting bolt passes, adjusting nuts on the adjusting bolt above and below the bridge piece, said T-slot and bolt being arranged to co-act and prevent rotation of the bolt. 80

3. In a device of the kind described, a side frame having a pair of spaced pedestal legs, a binder spanning the space between the lower ends of said legs and provided adjacent one leg with a slot extending vertically through and longitudinally of the binder, a journal box wedge bearing on the inner face of the leg adjacent said slot and provided at its lower end with a T-shaped slot opening through the bottom of the wedge, bolts securing said binder to the frame, an adjusting bolt having its head in the head portion of the wedge slot and its shank extending downwardly through the stem portion of the wedge slot and down through the slot in the binder, a locking plate having an opening therein through which the lower end of said bolt passes to fit closely therein, and bolts securing the locking plate against the under side of the binder to hold the bolt against movement longitudinally of the slot, a bridge plate carried by the last mentioned bolts and through which said adjusting bolt passes, adjusting nuts on the adjusting bolt above and below the bridge piece, said T-slot and bolt being arranged to co-act and prevent rotation of the bolt. 85
